(57) **CLAIM**

The ornamental design for a rear sensor housing, as shown and described.

DESCRIPTION

FIG. 1 is a rear perspective view of a rear sensor housing according to our design;

FIG. 2 is a front perspective view thereof;

FIG. 3 is a back elevation view thereof;

FIG. 4 is a front elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a front perspective view of a pair of rear sensor housings positioned on a first exemplary vehicle; and,

FIG. 10 is a front perspective view of a pair of rear sensor housings positioned on a second exemplary vehicle.

The broken lines shown in FIGS. 1-8 illustrate portions of the rear sensor housing that form no part of the claimed design. The broken lines shown in FIGS. 9 and 10 illustrate the exemplary vehicles, which form no part of the claimed design.

FIGS. 1-8 illustrate the rear sensor housing for use on a first side of a vehicle in a first embodiment. A second embodiment of the rear sensor housing is a mirror image of the first embodiment shown in FIGS. 1-8. The second embodiment is arranged for use on a second, opposite side of the vehicle. These mirror image arrangements are presented in the exemplary perspective views of FIGS. 9 and 10. The specific placement of the rear sensor housing in FIGS. 9-10 on the exemplary vehicles is for illustrative purposes only.
